UNITED STATES PATENT OFFICE

JOHN HANSEN, OF BETTENDORF, IOWA

POWER BALING MACHINE

Application filed May 26, 1926, Serial No. 111,701. Renewed August 20, 1930.

My invention has reference to power bal-
ing machines of the type set forth in my
former application for Letters Patent of the
United States filed April 20, 1925, Serial No.
5 24,425. In machines of the class mentioned,
which are designed for the baling of large
quantities of paper and similar material, the
compressive force is exerted through a heavy
plunger, or platen, which is at times moved
10 upwardly under no particular stress, and is at
other times moved downwardly under a con-
siderable compressive force, directed against
the contents of the machine. As a result the
power of the operating devices is being ap-
plied at one period in one direction and at
another in a contrary direction, resulting in
a considerable strain on the operative parts,
and requiring unusual durability and ef-
ficiency therein. One of the purposes of the
20 present invention is to provide a structure
and operating mechanism therein which is
specially calculated to meet the requirements
of a mechanism of the kind named.

Another feature thereof consists in a sub-
25 stantial formation of the floor of the press,
consisting of a single piece of cast metal. It
is usual to provide the floor of the paper re-
ceptacle, as well as the platen, with cross-
channels for use in passing cords or wires
30 round the completed bales, and in the present
device such channels are provided in the cast-
ing, instead of using spaced plates or blocks
of wood, as has been the practice. The present
arrangement provides a more rigid support
35 for the bales, and is more easily produced.

In the drawings:

Fig. 1 is a perspective view of the invention,
with portions cut away to more clearly
illustrate the same.

40 Fig. 2 is a front elevation thereof with the
base shown in longitudinal section.

Fig. 3 is a horizontal section of the casing
20 and parts contained therein, on the broken
line 3—3 of Fig. 4.

45 Fig. 4 is a vertical section thereof, on the
broken line 4—4 of Fig. 3.

The base of the machine is formed of a pair
of I-beams 1 and 2, spaced apart, and united
at their ends by cross-plates 3 and 4. Sup-
50 ported on the base between said plates is a

floor plate 5, provided at intervals with chan-
nels 6, all of the parts of said plate being in-
tegrally formed. Mounted on the cross-plates
3 and 4 is a pair of frames 7 and 8, united
near their upper ends by crossbeams 9, only 55
one of which is shown. Between said frames
is provided a receptacle of usual construction,
as shown at 10, of which the plate 5 forms the
floor. Threaded shafts 11 and 12 are sup-
ported at their upper ends from bearings 60
fixed to the upper ends of the frames 7 and
8, and are rotatable at their lower ends in
bearings in the plates 3 and 4, and movable
vertically on said shafts are travellers 13 and
14, to which is pivotally connected a frame 65
15, carrying a series of spaced platen bars 16.
Mechanism is also provided for operating the
platen frame, such as is set forth in said
former application, but said mechanism is not
specially involved in the present invention, 70
which relates more specially to the manner of
operating the shafts 11 and 12. Said platen
operating mechanism is therefore not par-
ticularly pointed out herein.

The lower ends of the shafts 11 and 12 75
are reduced in size and not provided with
threads, and secured thereon are helical gear
wheels 17 and 18, in mesh with pinions 21 and
22 on a shaft 23, on one end of which is a gear
wheel 24, actuated by a gear pinion 25, on the 80
drive-shaft of an electric motor 26, also con-
tained in the base of the machine. The gear
wheels 17 and 18 are enclosed in casings 19
and 20, which are supported from the plates
3 and 4, and in Fig. 3 the casing 20 is shown 85
projected into a casing 27, having bearings
at its ends for the support of the shaft 23.
Said bearings are provided with bushings 28
and 29, the last named bushing being held in
place by means of a collar 30, attached to the 90
end of the casing 27 by means of bolts 31. The
pinion 22 is held in place by a rib 32 fixed
in the shaft 23, and having play in a channel
in the pinion, which permits a limited move-
ment of the pinion in the casing 27. At each 95
end of the pinion is a pair of ball bearing
plates 33 and 34, having tracks in which op-
erate balls 35. The pinion 21 is similarly
supported from the casing 19, the appur-
tenant parts being the same as those shown 100

in Fig. 3, but not illustrated in the drawings.

The teeth on the wheels 17 and 18 and pinions 21 and 22 have a forty-five degree inclination, so that they work with equal facility with the shafts upon which they are positioned operating in either direction. When the shaft 23 is being rotated in a given direction the movement thereof will be imparted to the screw shafts 11 and 12 to cause the platen devices to move downwardly, and there will be an end thrust of the shaft in one direction. When it is desired to again raise the platen the direction of operation of the motor is reversed, causing a similar change of movement of the shaft 23. The thrust of said shaft is then in the opposite direction, and the change of said thrust from one end of the shaft to the other is brought about suddenly, and with a considerable amount of force. This change is fully met, however, by the ball-bearing mechanisms at the opposite ends of the pinions 21 and 22 which receive said thrust actions, without any hindrance to the operation of the shaft 23. By reason of the limited play permitted said pinions longitudinally of the shaft danger of the teeth on said pinions binding with the teeth of the gear wheels with which they operate is eliminated.

It will be observed that the invention is specially designed for use in communicating the movement of a main shaft to a threaded shaft at right angles therewith, where the stress received by the threaded shaft frequently shifts from one end thereof to the other.

If it is desired to repair or replace any of the pinion parts this can be readily accomplished by removing the collar 30 and slipping the bushings 28 and 29, ball bearing mechanisms and gear pinion between the same out through the end of the casing 27, the diameter of said parts being slightly less than the bore of the casing.

What I claim, and desire to secure by Letters Patent, is:

In a power baling machine, a base formed of spaced longitudinal beams, cross-plates supported on the ends thereof, a receptacle on said base and floor therefor formed of a single cast metal plate provided at regular intervals with downwardly projected supporting ribs having channels in their upper faces, threaded shafts supported vertically at the ends of said base, travellers on said shafts, gear wheels on said shafts, a drive shaft and gear wheels thereon in mesh with said first named gear wheels, and means for imparting rotation to said drive shaft in a given direction or the reverse thereof.

In testimony whereof I affix my signature.
JOHN HANSEN.
